(57) **CLAIM**

The ornamental design for a surgical stapling device, as shown and described.

DESCRIPTION

FIG. 1 is a perspective view of a surgical stapling device showing our new design;

FIG. 2 is a side elevational view thereof, the opposite side elevational view being a mirror image thereto;

FIG. 3 is a top plan view thereof;

FIG. 4 is a rear elevational view thereof;

FIG. 5 is a front elevational view thereof; and,

FIG. 6 is a bottom elevational view thereof.
